PHASE CORRECTOR FOR TELEGRAPH SYSTEMS

Eugene R. Shenk, Brooklyn, N. Y., assignor to
 Radio Corporation of America, a corporation of
 Delaware

Application March 30, 1940, Serial No. 326,902

7 Claims. (Cl. 178—69.5)

This invention relates to improvements in a phase corrector for the distributor of a telegraph system. In order to maintain a receiving distributor in phase synchronism with the speed of transmission of telegraph signals, it is necessary that the signals shall produce a corrective action whenever the speed of the receiving distributor departs from that of the transmitting distributor.

In phase correctors such as have been used in the past it has been common practice to obtain a corrective action by the use of the signal elements themselves in combination with locally derived pulses, such as may be produced by means controlled by the distributor. Usually such systems depended upon the relationship between the front edge of a marking signal impulse and a locally derived impulse.

Improvements over the previously known and practiced methods of phase correction have been disclosed by Richard E. Mathes in his U. S. Patent No. 2,212,447, dated August 20, 1940, and in application Serial No. 316,458, which was filed January 31, 1940, by Gilbert R. Clark. The Clark application was assigned to the assignee of the instant application. In the systems of Mathes and of Clark the times of occurrence of two local circuit closures are compared one with the front edge of a marking impulse and the other with the back edge of such a marking impulse. Two distinct time intervals were therefore, derived, the durations of these intervals being differentiated from one another in such manner as to produce the necessary phase correction of a distributor.

The device disclosed in the instant application follows certain of the teachings of Mathes and of Clark, as above explained. However, I have found that the heretofore known systems may be made more dependable in their operating characteristics and the circuit arrangements are subject to simplification in a manner such as will be hereinafter set forth in more detail.

It is an object of my invention to provide a dependable circuit arrangement for correcting the phase of a telegraph distributor such as used in multiplex telegraphy, and to provide means for measuring two time intervals, one of which elapses between the front edge of a marking signal and a local impulse near the normal center of a time allotment for dot unit impulse reception, and to compare this time interval with another time interval which starts from a moment near the center of the unit signal time

allotment and terminates at the back edge of the marking signal.

It is another object of my invention to provide a phase correction system wherein use is made of a "pulse wheel", rotatable integrally with the distributor, for derivation of local impulses whose phase is to be compared with the phase of the incoming signals.

It is another object of my invention to provide simplified circuit arrangements which eliminate the necessity for the use of certain filtering means heretofore thought to be essential.

It is still another object of my invention to provide a phase correction circuit having output terminals which may be connected to any one of a number of different utilization devices, either for directly controlling the phase of a distributor motor or for adjusting the frequency of an oscillator, such as may be used to maintain any desired telegraph apparatus in synchronism.

My invention will now be described in detail, reference being made to the accompanying drawings in which

Figure 1 shows diagrammatically a preferred circuit arrangement including the essential elements in combination for carrying out the invention; and

Figs. 2 to 8 inclusive are plots of electric impulses which occur in various parts of the circuit arrangement. These plots are all drawn to the same horizontal time scale in order to show the correlation of essential operations in response to signals.

In the following description of a preferred embodiment of my invention all elements referenced V1, V2, V3, etc., will be understood to be discharge tubes, whether of the vacuum type or of the gas-filled ionization discharge type. The gas-filled tubes, however, are conventionally designated in Fig. 1 by means of a black spot in the discharge zone.

Furthermore, the several resistors are referenced R1, R2, R3, etc., while the several capacitors are referenced C1, C2, C3, etc. Specific reference to each of the tubes, resistors and capacitors will, for the sake of brevity, be frequently made by their identifying symbols alone.

The two measured time intervals which are to be compared for purposes of phase correction of the distributor are obtained as follows:

The first or front end interval starts with the front edge of a marking signal impulse and terminates with the development of a local impulse designated P across resistor R26, this impulse being derived from a magnetic pick-up coil 5,

whose pole pieces are positioned adjacent the orbit of a phonic wheel 6 having a suitable number of teeth therein, located in appropriate positions for producing a change of magnetic reluctance in the field of the coil 5. The phonic wheel 6 is mounted on the shaft with the distributor whose phase is to be corrected.

The second time interval to be measured starts with a Q-pulse across resistor R1, as developed in a pick-up coil 1 whose pole pieces are positioned adjacent the orbit of the teeth in the phonic wheel 6. The termination of this back end time interval is produced at the back edge of a marking signal impulse.

One or both of the pick-up coils 5 and 1 may be oriented about the axis of the phonic wheel 6 so as to cause these impulses to be generated, one immediately before and the other immediately after the normal center of reception of a marking impulse of dot unit length.

As will be hereinafter shown, the front end integration period is represented by a charge stored on condenser C14, while the back end integration period is correspondingly represented by a charge stored on condenser C5. These charges are held until a space occurs following a marking impulse. If, however, the marking impulse is of longer duration than one dot or baud, the successive charges stored on condenser C5 are wiped out until the last one preceding a spacing signal, so that, regardless of the length of the marking signal, there is always a comparison to be made between the effective charges on C14 and C5 suitable for purposes of applying correction to the receiving distributor.

Differentiation between the charges on C14 and C5 respectively is manifested by means of two triode tubes V14 and V15 arranged in a differential circuit relationship, their anodes being interconnected through a resistive circuit at the center of which direct current from a +B source is applied. The relative conductivity across the space paths of V14 and V15 determines the potential drop across R38, R39 and R40 in relation to that across R41, R42 and R43. Since, however, R40 and R43 constitute bias resistors in the input circuit of a discharge tube V20, said input circuit including an independent grid biasing source 51, it will be seen that this triode tube V20 is in position to be controlled by the sense of polarity of the potential drop across these resistors R40 and R43.

The tubes V14 and V15 are rendered conductive only during spacing intervals and the amount of current flowing in each is determined by the charges respectively stored in capacitors C14 and C5. Hence the anode circuits of V14 and V15 will carry comparable currents through the resistors R40 and R43, such as may be utilized in any preferred device or circuit arrangement for maintaining synchronism of the receiving apparatus with respect to the incoming signals. Such a synchronizing device may, for example, be in accordance with the disclosure of Clark in his aforementioned application, wherein a three-position relay was used. The double winding of that relay was disposed correspondingly to the resistors R40 and R43 as herein shown in Fig. 1. Alternatively the synchronizing device may include an oscillator whose frequency is controlled by a reactor, the value of which depends on the differential between the currents in the output circuits of the tubes V14 and V15. A suitable oscillator circuit of that type is disclosed herein, as well as in my copending application Serial No.

326,903, filed March 30, 1940. In the respective cases, however, the oscillator is claimed only as an element in combination with features by which the two disclosures are patentably distinguished.

5 I will now explain how the incoming signals and the locally derived impulses from the pick-up coils 5 and 1 may be made effective to store charges on the condensers C14 and C5, so that the proper control of the tubes V14 and V15 may be obtained.

The received multiplex signal consisting of a tone for mark and no tone for space is passed through transformer T and rectified by a full wave rectifier tube V1. A diagram of the signal 10 input before rectification is shown in Fig. 2.

The rectified signal voltage appears across resistor R17 in the polarity indicated, that is, with the positive end connected to ground.

The negative signal voltage is applied, together 20 with a threshold determining voltage which appears across R18, to the control grid of electron discharge tube V2, thereby shifting this grid from a normal zero bias to a cut-off bias. V2 is, therefore, blocked for the duration of the marking signal.

A connection is also provided from a mid-tap on the secondary of transformer T to a potentiometer R29, and thence through resistors R28 and R30 to the grids of tubes V14 and V15. The 30 potentiometer R29 is connected at one end to a source of biasing potential, -C, more negative than ground. Normally, therefore, there is a potential gradient across the potentiometer R29 from its -C terminal to its other terminal and thence through R17 to ground. This potential gradient is, therefore, available as a biasing potential on the grids of tubes V14 and V15. The tubes V14 and V15 are, therefore, controlled only during spacing intervals and when they receive a positive bias across resistors R28 and R30 respectively, as derived from the discharging of condensers C14 and C5, as will be hereinafter explained. V14 and V15 are, however, maintained at cut-off bias during each marking interval by virtue of the rectified negative potential at the center tap of the secondary winding on transformer T which is additive with the above mentioned -C potential.

The control of V2 by the negative signal voltage 50 is such as to bias this tube to cut-off and hence to raise its anode potential to the full +B voltage. A positive impulse is, therefore, impressed across C9 which produces a potential drop in R25. This impulse is reflected into a circuit leading to the 55 grids of two gaseous discharge tubes V4 and V12 for igniting the same at the front edge of a marking impulse. The discharge in V12 is only momentary and serves to dissipate any residual charge on C14 down to a reference voltage, at 60 which V12 becomes automatically extinguished.

When the gaseous tube V4 strikes, an impulse is impressed across C11 which lowers the potential on the anode of V6 momentarily, and to such a value as to extinguish this tube. V4 and V6, because of their intercoupled anodes, are said to be in "back-to-back" relation to one another. Condenser C11 is then quickly charged positive on the side of the tube V6. C14 charges through rectifier tube V10 and resistors R24 and R5 while V6 is extinguished. During this interval C14 charges to an extent practically proportional to the time interval, it being understood that the capacitance of C14 is sufficiently great to meet this requirement.

70 The front end period to be integrated is ter-

minated by a local impulse designated P which is derived, as stated above, from the pick-up coil 5. Such an impulse is applied negatively across resistor R37 to the grid of V3 which blocks momentarily in response thereto. When the anode of V3 rises to +B voltage, a positive P-pulse is impressed across C8 and R26, the latter being in circuit between the -C terminal of a biasing source and the grids of V6 and V7. Disregarding V7 for the moment, the positive impulse causes V6 to strike. At this moment V6 extinguishes V4, since C11 is now momentarily charged in the reverse direction from formerly. The reduced voltage on the anode of V6 terminates the current flow through V10, since the cathode thereof is now positively polarized by C14 and is more positive than the anode of V6. V10, therefore, serves to isolate the charge on C14 and to store the same until it can be utilized for comparison purposes during a space interval following a marking period.

At the commencement of the back end integration period a Q-pulse is delivered by the impulse coil 1. The moment when this takes place is slightly delayed after the normal center of a baud has been reached. This delay is equal to the anticipation period of the P-pulse in advance of the baud center. In order to render the Q-pulse effective only during marking periods, I provide a vacuum discharge tube V8 having an input circuit which includes R1 and a junction point between R18 and R19, and thence through R18 and R17 to ground. The junction point between R18 and R19 is also connected through R19 and R20 to the +B terminal and is affected by the rectified signal voltage. Consequently V8 which normally draws current through R2 is biased to cut-off by and during a marking signal. It is only at such times that V9 is supplied with sufficient anode potential to amplify a Q-pulse from the pick-up coil 1.

V9 is operating at zero bias and when it receives a negative pulse from the pick-up coil 1 this pulse is delivered positively after amplification across C2 and develops a voltage across R7 connected between the -C terminal and bias resistor R6 leading to the grid of a gaseous tube V5. In shunt with R6 and the grid of V5 is a grid resistor R13 and the grid of a gaseous tube V13.

V5 and V13 are both ignited by a Q-pulse. The discharge in V13, however, lasts only until it can dissipate a residual charge on C5 and reduce the voltage thereof to a reference point at which V13 becomes automatically extinguished.

When V5 strikes, C4 momentarily reduces the anode voltage on V1 to a point where this tube is extinguished. Immediately therefore the anode of V1 rises to full +B voltage and C5 starts to charge by virtue of the conductivity of V11 which is a diode rectifier. This charging current flows through R8, R11 and V11.

In case the marking impulse is of dot unit length, or one baud, the charge stored on C5, as above described, will be effective immediately upon the termination of a marking impulse and will produce a discharge in V15 commensurate with and representing the back end integration period. If, however, the marking impulse is of longer duration, then it is necessary to successively wipe out the charge on C5 by a P-pulse and to resume charging the same in response to a Q-pulse. V7 is ignited by a P-pulse. At that moment V5 becomes extinguished and is prepared to receive a succeeding Q-pulse. The ineffective charging times of C5 are indicated in

Fig. 8. The effective charging times, however, are indicated in Fig. 7, where the Q-pulse is followed by the termination of the marking signal as denoted by the occurrence of an S-pulse. This is distinguished from a P-pulse because it occurs at a different time and in response to the commencement of the conductive period of V2, that is, at the commencement of a spacing period.

V2, when its anode voltage is reduced in response to the cessation of the rectified signal voltage, momentarily biases V3 to cut-off. The result of this action is to impress a positive S-pulse across C8 and R26, the same as occurred in response to a P-pulse from the pick-up coil 5.

It will be seen from the above, and from a comparison of Figs. 2 to 8 inclusive, that the various pulses designated M, P, Q and S are caused to control the charging times on C5 and C14 in such manner that these charges may be differentiated during a spacing interval. The charge stored on C14 represents the front end integration period, while the charge stored on C5 represents the back end integration period.

The spacing signal itself, as has heretofore been shown, changes the bias on the grids of V14 and V15 so that the voltages of the condensers C14 and C5 may control the conductivity of these tubes differentially.

It is known in the art that a multiplex distributor may be phase-controlled by a vacuum tube oscillator. For example, such a system is disclosed in United States Patent No. 1,747,248, granted February 18, 1930, to W. A. Knoop. Other systems of speed control and phase correction of a multiplex distributor are also known and may be adopted in connection with the correction unit herein disclosed.

In order that the frequency of an oscillator may be conveniently controlled by a given voltage, as obtained from the relatively conductive states of the tubes V14 and V15, I have shown a system of resistors connected in the output circuits of these tubes. The +B voltage is applied to the mid-point between the output circuits for the two tubes V14 and V15. This voltage is impressed across R40, R39 and R38 to the anode of V14. The +B voltage is also impressed across R43, R42 and R41 to the anode of V15. In order to smooth out the action of the tubes capacitor C15 is connected between the +B terminal and the junction between R38 and R39. A capacitor C16 is similarly disposed between the +B terminal and the junction between R41 and R42. An amplifier tube V20 has an input circuit which includes its control grid, resistors R40 and R43, and an independent source 51 of C-potential, whose positive terminal is connected to the cathode of V20. V20 requires also an independent B-source 50 in its output circuit connected between the cathode and anode through an inductive reactance L. The cathode of V20 is provided with a capacitive shunt C20 to ground. The measured voltage difference between R40 and R43, as determined by the conductivity of V14 and V15 respectively, determines the bias potential on V20. The output circuit of this tube, therefore, reflects the results of the integration of time intervals, one representing the front end and the other the back end of a marking signal.

The resultant control of an oscillator whose input circuit includes a resonant unit may, therefore, be understood, this control being impressed across capacitor C21. The resonant circuit is indicated at 22, one end of which is

grounded, the other end being connected to the grid of an oscillator tube V23.

Because V23 is self-biased there will be no bias when the circuit is first turned on. Therefore, a pulse of plate current will flow in V23. This pulse is fed to V25 which amplifies and limits its amplitude as well as introducing a phase shift of substantially 180°. This amplified, inverted pulse is fed back to the tank 22, in which an oscillator current is set up. Therefore, a voltage of substantially sine wave formation appears across the tank. This voltage initiates another change of current in V23 and the cycle is repeated.

The oscillator V23 has a grid-to-cathode circuit which includes potentiometer 54 and a resistor 55. Capacitor 56 is in shunt with resistor 55. Amplifier tube V24 has its cathode connected to the cathode of V23. V24 possesses a control grid circuit which includes a tap on potentiometer 54. V24 is, therefore, controlled in phase with V23 and its output power may be adjusted to any desired value by means of the adjustable tap on potentiometer 54. The output circuit of V24 includes the primary of a transformer 52 and an anode potential source which is common to the output circuit of V25. The secondary of transformer 52 delivers a controlled output frequency which is suitable for distributor phase correction purposes.

I claim:

1. A system for synchronizing a telegraph distributor with a train of incoming marking signals comprising means for producing in the following sequence four species of control pulses M, P, Q and S, of which M and S are responses to the arrival of the front and back edges respectively of each marking signal, and P and Q are timed to occur at equal intervals before and after a reference phase of said distributor, electrical means for differentiating between the duration of M-to-P intervals and Q-to-S intervals, an oscillator having frequency control means subject to the influence of said differentiating means, and means for causing said oscillator to correct the phase of said distributor.

2. A system according to claim 1 in which said differentiating means comprises a capacitor receptive of a charge proportionate to the M-to-P interval and a second capacitor receptive of a charge proportionate to the Q-to-S interval, a pair of vacuum discharge tubes and means operative during a spacing period for subjecting one of said tubes to the control voltage of the first said capacitor and for subjecting the second of said tubes to the control voltage of the second said capacitor.

3. In a synchronous telegraph system for the reception of keyed signals the marking elements of which are of baud length and multiples thereof, means including two capacitors for accumulating comparable charges, pulse generating means for so timing the occurrence and duration of said charges that one commences at the front edge of a marking element and terminates prior to the arrival of the next succeeding baud center, and the second of said charges commences after the arrival of a baud center next preceding the back edge of said marking element and terminates on arrival of said back edge, means for storing said charges, means operative during the next succeeding spacing element of the signals for differentiating between the values of said charges,

a distributor, means including an electron discharge tube oscillator for controlling the phase of said distributor, and means for causing the frequency of said oscillator to be varied in accordance with the differentiation between said charges.

4. In a phase corrector for a receiving telegraph distributor, a magnetic pulse wheel rotatable with the rotor of said distributor, a pair of pick-up coils each arranged to generate a periodic succession of impulses in fixed synchronous relation to the rotation of said pulse wheel, means responsive to the reception of the front edge of a marking signal element for initiating an ionization discharge, means responsive to the next succeeding impulse from one of said pick-up coils for extinguishing said ionization discharge, a capacitor for storing a charge substantially proportional to the duration of said ionization discharge, means responsive to an impulse from the second of said pick-up coils for initiating a second ionization discharge, means responsive to the reception of the back edge of said marking signal for extinguishing said second ionization discharge, a second capacitor for storing a charge substantially proportional to the duration of said second ionization discharge, means operative during a spacing signal for comparing the voltages of the two charges thus stored, an oscillator for controlling the speed of said distributor, and means operative in accordance with the magnitude and sense of the voltage difference between said two charges for synchronizing said oscillator and the distributor with the incoming signals.

5. A phase corrector in accordance with claim 4 and including means for discharging each of said two capacitors down to a predetermined reference voltage prior to the accumulation thereon of the charges to be compared.

6. A phase corrector in accordance with claim 4 and including means to nullify the effects of storing charges on the second capacitor when accumulated during a relatively long marking period and prior to the generation by said second pick-up coil of an impulse which next precedes the arrival of the back edge of the marking impulse.

7. In combination, a source of two synchronizing impulses, one being effective on the arrival of the front edge of a marking signal, the second being effective on the arrival of the back edge of said marking signal, a periodic device having means controlled thereby for delivering two local pulses, one in advance of and the other equally in arrears of the baud center as determined by said periodic device, means including two separate capacitors for storing charges thereon which represent two time periods to be differentiated, one of said periods extending from the front edge of a marking impulse to the next succeeding local pulse, the other of said periods extending backwards from the back edge of said marking impulse to the next preceding local pulse, an oscillator, having a frequency-determining element in its input circuit, and means under control of currents derived from the differentiation of said stored charges for so adjusting the value of said frequency determining element as to effect synchronization of said periodic device with said signals.

EUGENE R. SHENK.
